HATCH PLUG

Charles David Bonsall, Chicago, Ill., assignor to
Standard Railway Equipment Manufacturing
Company, a corporation of Delaware

Original application February 15, 1940, Serial No.
319,047. Divided and this application April 4,
1940, Serial No. 327,825

6 Claims. (Cl. 105—377)

The subject matter hereof is divided out of my copending application Serial No. 319,047 filed February 15, 1940, for patent for Hatch plug.

My invention relates to hatch plugs and particularly to hatch plugs of the kind that are used for closing the hatchways of refrigerator cars. The principal objects of my invention are to devise a plug that will be light, that will have its insulating material adequately protected against ingress of moisture, dirt and other foreign matter, that will be substantially free from the injurious effects of warping, and which is so designed that parts that are subject to wear can be easily and rapidly replaced without removing the refrigerator car from its train. The invention consists principally in making the plug in the form of a hollow metal container filled with insulating material and with provision for securing around its sides nailing strips upon which suitable padding is nailed, the nailing strips being preferably detachably mounted. The invention also consists in the parts and combinations of parts hereinafter described and claimed.

In the accompanying drawing, wherein like reference numerals refer to like parts wherever they occur,

Fig. 1 is a plan view, partly in horizontal section, of a hatch plug embodying my invention;

Fig. 2 is a vertical section through the plug on the line 2—2 in Fig. 1;

Fig. 3 is an enlarged vertical section through the plug on the line 3—3 in Fig. 1;

Fig. 4 is a section, similar to Fig. 3, showing a modification of the invention; and

Fig. 5 is a perspective view of the bottom strap shown in Fig. 4.

The hatch plug shown in Figs. 1, 2 and 3 of the accompanying drawing comprises four main members, namely, a rectangular metal pan-shaped bottom member G with rounded corners, a metal top or cover plate D, a sectional wooden filler or nailing strip E2 and a compressible padding F. The pan-shaped bottom or body member G is pressed up from a sheet of metal with sloping or upwardly flaring side walls 20 and with an outstanding horizontal rim or marginal flange 21 at the top thereof. The chamber between said bottom and the top is filled with any suitable insulating material 6, such, for instance, as loosely packed or felted hair or vegetable fibers. The metal cover D, which is preferably stiffened or strengthened by hollow upstanding ribs 7 therein, seats on and is secured flatwise to the marginal flange 21 of the pan-shaped bottom member G preferably by a continuous edge weld 8. The in-

sulating material 6 is thus sealed hermetically inside the metal shell formed by the pan-shaped body G and the cover plate D and consequently is protected against leakage of water or other leakage and against the ingress of dirt or other matter into said metal shell.

The rectangular pan-shaped body member G of the plug is smaller than the hatch opening for which it is designed, and its width and length are increased to fit said opening by means of the sectional wooden filler strip E2 which extends around the sides of said body member beneath the outstanding rim flange 21 thereof. As shown in the drawing, the filler strip E2, the outstanding rim flange 21 of the pan-shaped body member G and the closure plate D for said body member are all disposed with their outer edges in flush alinement. The filler strip E2 is secured by means of through bolts 9b that extend downwardly through registering openings provided therefor in the cover plate D, the outstanding rim flange 21 of the pan-shaped body member G and said filler strip E2. The bolts 9b are provided with nuts 10b that seat in countersinks provided therefor in the bottom face of the filler strip E2, said bottom face of said filler strip being preferably disposed substantially flush with the bottom of said body member G. As shown in the drawing, the filler strip E2 is made up of endwise abutting side and corner sections or blocks 11 and 12, respectively. Thus, the filler strip sections are easily, separably removable from the pan-shaped body member G of the plug by removing the securing bolts 9b therefor.

The filler strip E2 serves as a nailing strip for the compressible padding F. This padding preferably comprises a strip or strips B of waterproof canvas through whose lower margin brads or small barbed galvanized roofing nails or like fasteners 13 are driven into the lower portions of the filler blocks. Curled hair or other suitable packing material 15 is filled in between the canvas strip 13 and the face of the filler strip E2 and then the upper margin of the canvas strip is secured to the upper portion of said filler or nailing strip by fasteners similar to the fasteners for the lower margin of said canvas strip.

The construction illustrated in Figs. 4 and 5 is similar in all respects to that shown in Figs. 1, 2 and 3 except only that metal straps or strips 22 are welded to the bottom of the metal body G and extend outwardly underneath the filler blocks E2 with the through bolts 9b extending through them and with the bolt nuts 10b under-

neath said straps. Thus, the straps serve to more firmly hold the filler blocks in place.

The hatch plug construction hereinbefore described has numerous advantages. In the first place, it is considerably lighter than the wooden plugs commonly used. Its entire body portion, including the insulation, is permanently assembled, while those parts that are especially subject to wear and injury are easily replaceable without disturbing the body of the plug. Such repairs and replacements are so simple that they may be made while the car is at a regular icing station and without requiring the removal of the car from its train and with little or no delay of the train. As the top of the plug is welded to the sides, the insulating material is kept dry and uncontaminated and a lighter gage of metal may be used in the construction of the plug. Another advantage is that the wooden filler blocks afford great protection against injury by being struck by blocks of ice or other rough usage and thus said filler blocks make it practicable to use lighter gage metal than would otherwise be feasible. While the filler blocks are liable to take up moisture and warp, such warping does not affect the metal frame and is inconsequential because the filler block is not intended to contact with the wall and hatch opening.

What I claim is:

- 30 1. A hatch plug comprising a metal pan-shaped body member with an outstanding rim flange at the top only thereof, insulating material in said member and a metal cover plate for said body member secured to the rim flange thereof, a nailing strip extending around said body member beneath the rim flange thereof and detachably secured to said rim flange, and padding secured to the outer side face of said nailing strip.
- 40 2. A hatch plug comprising a metal pan-shaped body with an outstanding rim flange at the top thereof and a metal cover plate for said body seated on and secured to the rim flange thereof, a sectional wooden strip extending around said body beneath the rim flange thereof, metal straps secured to said body and extending outwardly beneath said wooden strip, bolts extending through said cover plate, rim flange, wooden strip and metal straps, and padding secured to the outer side face of said wooden strip.
- 50 3. A hatch plug comprising a metal pan-shaped body with upwardly flaring sides and an

outstanding rim flange at the top only thereof, insulating material in said body and a metal cover plate for said body seated on said rim flange, a nailing strip extending around said body beneath said rim flange and fitting the angle formed by said flaring sides and rim flange, bolts extending through said cover plate, rim flange and nailing strips, and padding secured to the outer side face of said nailing strip.

4. A hatch plug comprising a metal pan-shaped body with sloping sides and an outstanding rim flange at the top thereof, insulation in said body, a metal cover plate for said body seated on said rim flange with its edge substantially flush with and welded to the outer edge thereof, a sectional wooden strip extending around said body in the angle formed by said sloping sides and said rim flange with its outer face substantially flush with the outer edge of said rim flange and with its bottom substantially flush with the bottom of said body, metal straps welded to said bottom and extending outwardly beneath said wooden strip, bolts extending through said cover plate, rim flange, wooden strip and metal straps, and padding secured to the outer side face of said wooden strip.

5. A hatch plug comprising a metal pan-shaped body with sloping sides and an outstanding rim flange at the top thereof, insulation material in said body, a metal cover plate for said body seated on said rim flange with its edge substantially flush with and welded to the outer edge thereof, a wooden strip extending around said body and fitting the angle formed by said sloping sides and said rim flange with its outer face substantially flush with the outer edge of said rim flange and with its bottom substantially flush with the bottom of said body, bolts extending through said cover plate, rim flange and wooden strip, and padding secured to the outer side face of said wooden strip.

6. A hatch plug comprising a metal pan-shaped body member with an outstanding rim flange at the top thereof, insulating material in said member and a metal cover plate for said body member secured flatwise to the rim flange thereof by a continuous weld, a nailing strip extending around said body member beneath the rim flange thereof and detachably secured to said rim flange, and padding secured to the outer side face of said nailing strip.

CHARLES DAVID BONSALL.
